Primary Examiner — Ricky Pham(57) **CLAIM**

The ornamental design for a portable silicone warming board, as shown and described.

DESCRIPTION

FIG. 1 is a front, top and left-side perspective view of the portable silicone warming board showing my new design; FIG. 2 is a back, bottom and right-side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view, of circled portion 9, of FIG. 1, thereof; and,

FIG. 10 is an enlarged view, of circled portion 10, of FIG. 2, thereof.

The broken lines throughout the drawing figures depict portions of the portable silicone warming board that form no part of the claimed design.

The dot-dash broken lines depict the boundaries of the FIGS. 1, 2, 9 and 10 enlargement that forms no part of the claimed design.

1 Claim, 10 Drawing Sheets(56)
